METHOD AND MEANS FOR STUDYING
SOUND

Frank Morse Robb, Belleville, Ontario, Canada

Application November 16, 1934, Serial No. 753,247

5 Claims. (Cl. 179—100.2)

This invention relates to methods and means for studying sound, and is a companion invention to the one covered by applicant's patent number 1,964,929, issued July 3, 1934, entitled Methods and apparatus for studying sound.

An object of the invention is to provide an electrical instrument in which an opposing current is generated in the circuit which entirely neutralizes and wipes out what is known variously as the slot tone, scanning tone, disc tone or inherent tone, thereby maintaining the output voltage line at zero until a waveform mask is placed before the scanning disc, in which case only the natural tone of the wave form will be heard.

Another object of the invention is to provide a method and means for obtaining a musical tone from a waveform mask without hearing the scanning tone along with it, said method and means being accomplished not by a photo-electric circuit but by electro-magnetic means, which effect this elimination of the scanning tone while still permitting the full and natural sound of the waveform being scanned.

All these and other objects as suggested here below are attained by the methods and means now to be described, and illustrated in the accompanying drawing, in which—

Figure 1 shows the face of a scanning wheel with three waveform tabs and the pickup and field coils in different positions.

Fig. 2 shows a side elevational view of the scanning wheel of Fig. 1, positioned in operating relation between the neutralizing pickup and the tone pickup.

Fig. 3 shows a diametral cross sectional view of a drum type of scanner (as distinguished from the disc type of the previous views), with the neutralizing and the tone pickup coils on the South and North Poles of a single magnet.

Fig. 4 is a plan view of a sheet iron tab such as is used to cut the waveform in.

Fig. 5 shows the tab of Fig. 4 with a wave form cut therein, and

Fig. 6 shows the belt type of scanner with three tone pickups and the neutralizing pickup.

Like numerals refer to like parts throughout the several views.

In applicant's previous patent, above mentioned, is shown the construction of a photo-electric instrument which, when in operation, produces no sound until the shadow of a wave form falls upon its screen or aperture; and which is so designed that it generates sound waves in the air which in their form are a faithful reproduction of the waveform shadow which has been cast

upon the aperture of the instrument. In other words, this photo-electric instrument has no inherent tone of its own, but will give out only the quality of sound represented by the contour of the shadow cast on its aperture, which is of utmost importance in the precise study of sound waves and musical qualities.

Now while this photo-electric apparatus is very successful, it has seemed advantageous to make an instrument still more simple in design which can be used for the same purposes. Therefore applicant has invented a new apparatus using the principle of the generation of electric current in coils through which is passing a magnetic flux. In this new apparatus an opposing current is generated in the circuit which entirely neutralizes and wipes out what is known variously as the slot tone, scanning tone, disc tone or inherent tone, thereby maintaining the output voltage line at zero until a waveform mask is placed before the scanning disc, in which case only the natural tone of the waveform will be heard.

Until applicant's invention of the photo-electric apparatus as disclosed in Patent 1,964,929 above mentioned, there was no known means of obtaining a musical tone from a waveform mask without hearing the scanning tone along with it.

After the above invention there was still no known means of accomplishing this particular result in any circuit other than a photo-electric one until this invention of the electro-magnetic design as disclosed here, which effects this same elimination of the scanning tone while still permitting the full and natural sound of the waveform being scanned.

The scanning wheel of Fig. 1 consists of a plurality of equi-spaced iron ribs 10 set in a brass or bakelite disc 11.

On scanning wheel 10—11 are shown three waveform tabs 12, 13, 14, the pickup and field coils being represented by dotted lines 15. The arrow shows the direction of rotation. Tabs 12 and 13 are in normal position, and it will be noted that the shape of these tabs, apart from the waveform, is such that one scanning rib will cross over flush at the one end just as another rib is passing off flush at the other end. Tab 14 is shown turned on its axis to an angle as described herebelow.

In Fig. 2 the scanning wheel 10—11 is shown on its edge to be rotated about axle 16. The neutralizing pickup is shown at 17 and the tone pickup at 18. That is to say 17 and 18 show the larger field coils and 17A and 18A show the detail of the narrow pickup coils. By turning the knurled

thumb nut 19 the pickup will be advanced or re-treated through the threaded support 20, and the waveform tab thus moved closer to or farther from the scanner. A twist of the little handle on the magnet core, or 21, will turn the waveform tab 12 (for example) around on its axis. Members 19 and 21 are of soft iron, while support 20 is of brass or other non-magnetic material.

In this view the south pole is at 11A and the 10 north pole opposite at 18A. Member 21 connects with and turns the rotatable magnet core 22. In this view washers are shown at 23 and knurled nut 19 connects with and turns hollow magnet 24 containing an adjusting thread adapted to be screwed through companion threads in support 20.

In Fig. 3 is shown a drum type of scanning wheel 25 driven by axle 26, said member 25 being made of iron and containing slots 27. The 20 field coil is shown at 28, the pickup coils at 29 and 30, the waveform tab at 12, and the north and south poles respectively designated by "N" and "S". In this view the neutralizing and tone pickup coils are shown on the south and north poles of a single magnet. The waveform tab 12 is shown on the north pole.

In Fig. 4 the sheet iron tab to be used to cut the waveform is shown at 31 and the waveform cut in such tab is shown in Fig. 5 at 32.

In Fig. 6 the speaker is shown at 33, the amplifier at 34, a variable resistance at 35, a six volt current supply at 36, and the belt type of scanner comprises two pulleys 37-37 adapted to be rotated in direction of the arrows to in turn move the belt scanner 38. There is also shown three tone pickups 39, 40 and 41, and the neutralizing pickup 42. A waveform tab 12 is shown on the pole of pickup 41.

The circuit in Fig. 6 is shown for several tone 40 pickups with a single neutralizing pickup, as described above, this neutralizing pickup having a multiple wind field coil. When a contact is made by closing any one of switches 43, a current is sent into a field coil on its corresponding tone pickups 39, 40, 41 and also into one of the windings on the field of the pickup 42. Thus the neutralizing pickup is always energized in proper proportion for one, two or more tone pickups. The pickup coils are here shown permanently in circuit. The variable resistance 35 permits the neutralizing current from the pickup 42 to be cut down in case it is a little too strong. Of course the N's in this figure designate north pole and S 55 designates south pole.

Thus it will be seen that in the present invention the obtaining of natural quality of sound from a waveform member without any accompanying scanning tone is effected by means of 60 opposing poles of magnets having pickup coils on them, the poles being evenly shaped and so placed in relation to the scanning slots or ribs that the positive current generated in one pickup coil at any given instant will be exactly equal to the negative current generated in the other pickup coil. The two currents will thus neutralize each other, and the output of the circuit will be zero, until an iron or steel waveform member be placed on the pole of one magnet, when 65 the balance will be upset and a current will appear in the circuit; and the electrical waveform of this current will have the same profile as the waveform on the iron member, and will not be 70 distorted by any scanning tone as would be the 75

case if the neutralizing effect as set forth here were not employed.

It is possible to use one neutralizing pickup of greater magnetic strength to balance out the scanning tone of several other pickups of opposing magnetic poles.

In the operation of this instrument the desired waveforms to be heard are cut in the thin iron blanks with a small pair of shears or by other means, and these waveform tabs are then placed 10 on the poles of the magnets and the magnets themselves are then screwed up until there is but a minute air gap between the tabs and the scanning wheel. The iron ribs of the scanner passing over the iron waveform set up a magnetic flux in the magnet, the character of which depends on the shape of the waveform on the tab. This flux sets up an electric current in the pickup coil which must have that same waveform.

As the waveform tabs are so shaped in relation to the ribs of the scanner that one rib is just passing off the tab as the next rib is coming on, the generated current will be continuous and earphones or other sounding apparatus connected 25 in the circuit will give out a sustained tone, the musical quality of which will be that of the waveform which has been cut on the tab. For instance, if the waveform of a baritone human 30 voice has been cut on the tab, the earphones will give out a baritone voice tone, and that tone will be natural and free from any additional superimposed tone from the scanner itself.

This is of vital importance. Without any balancing out, a scanning wheel gives out a "reed pipe" organ tone, and when one wishes to investigate a particular waveform, say that of a cello, one does not wish to hear it accompanied and drowned out by this reed-like organ tone. Hence 35 the value of this invention, the proof of which 40 is seen in the cathode ray oscillograph, the waveform on the screen taking the identical shape of that on the pickup tab, and being free from distortion by any unwanted waveform from the 45 scanner itself.

It is sometimes interesting, however, to distort the waveform deliberately by turning the waveform profile on the tab to an angle with the scanning ribs. This results in an exaggeration 50 of some of the partials of the tone and a suppression of others and produces an entirely new tone. To accomplish this the pickups are made with poles which can be revolved and thus be made to twist the waveform tabs on them to different positions.

The invention includes also the use of what is believed to be an entirely new method of sounding tones, the advantages of which are that all pickup coils remain continuously in the circuit, 60 making the designing of a circuit for a multiplicity of pickups a simple matter; and the tones sound and cease without the usual annoying click caused by the make and break of contacts; also the attack is pleasant, the tones coming on with 65 a slight scoop as with all musical instruments.

This new method, then, consists of the use of field coils on the pickup magnets in addition to the pickup coils, contact to sound the tones being made to the field coils which thus being 70 energized produce a strong magnetism at the pickup poles. Very soft iron, which loses its magnetism instantaneously and completely on the cessation of the current in the field coils, is used in these pickup magnets, and the same type 75

of iron is used for the waveform tabs and for the ribs on the scanning wheel.

With this arrangement, although several pickup coils are in the circuit, those pickups which have had waveform tabs placed at their poles still will not generate any tone current until the proper contact keys are pressed to energize their field coils. In other words, there can be no magnetic flux at the pickup poles unless there is current in the field coils, and when there is no flux there will be no tone current generated in the pickup coils.

There has heretofore been proposed the use of tone wheels in combination with varied shapes of pole pieces for the pickup magnets. But such pole pieces are intended merely to alter slightly the characteristics of the wave form which is on the tone wheel. But this applicant is the first to use a scanning disc which itself has no wave-form other than its slotting, and which is intended to scan a natural wave form on a pole piece in exact repetition and with such exact dimensions of the wave form in relation to the distance between the slots in the scanning disc or ribs of iron, as the case may be.

In the prior invention referred to above, there is simply a tone wheel with a varied pole piece, the combination being used to reproduce whatever tone has been recorded or cut on the disc, and to permit slight variations or exaggerations of this tone by altering the shape of the pole piece.

But in applicant's invention, a natural musical wave form is reproduced without any scanning tone along with it, because of the special shape and dimensions, as explained, which results in the entire suppression of the scanning tone, or what might be called the disc tone, and which thereby allows the natural production of the wave form on the pole piece without distortion.

Having now described the invention, what is claimed as new and for which Letters Patent of the United States is desired, is:

1. The combination with a scanning member free of any wave form but having ribs or scanners of magnetic material, of pickups of opposing magnetic poles so shaped and placed that the currents generated in their pickup coils oppose and neutralize each other in the circuit to result in a zero output voltage. 10

2. The invention as in claim 1, including the use of waveform tabs of such shape that one scanning rib will be just starting to pass over the one end of the tab as another rib is passing off the other end, to thus produce a continuous generation of the electrical waveform without gap or overlap. 15

3. The invention as in claim 1, including the use of revolving pickup poles so arranged that the waveform tabs may be turned to different positions in regard to the scanning ribs, to thereby produce different distortions of tone. 20

4. The invention as in claim 1, including the use of pickup coils permanently in circuit, with their magnets and the waveform tabs and scanning ribs of a kind of metal which drops its magnetism instantly, and including field coils on the pickups connected to contact keys which feed energizing current when contact is made. 25

5. In an electro-magnetic circuit, means of obtaining a musical tone from a waveform mask without hearing the scanning tone along with it, said means including a scanning disc free of any wave form and means associated therewith for generating an opposing current in the circuit to entirely neutralize and wipe out what is variously known as the scanning tone, slot tone, disc tone or inherent tone. 30 35
